UNITED STATES PATENT OFFICE

2,464,118

AUTOMOBILE REPAIR TOOL

Guy A. Countryman, Ashland, Ohio

Application November 15, 1946, Serial No. 710,114

4 Claims. (Cl. 153—48)

1

The invention relates to tools adapted to be used in combination with a pressure device, such as a jack for straightening and bending sheet metal members such as automobile bodies, fenders, doors, hoods and the like.

It is present practice, in the repairing of automobile bodies, fenders and the like, to provide body tools comprising a pressure applying strut member adapted to be operatively connected to a pressure producing device, such as a hydraulic jack, screw jack or the like, and having a tool in the form of a pressure head detachably connected to the end of the strut member for contacting a portion of the automobile body, fender or the like to straighten or bend the same.

It is sometimes necessary in the operation of such tools to apply the pressure of the head directly against a painted or finished surface which may be marred or scratched thereby.

The object of the present invention is to provide such a body tool having a pressure applying head covered with a suitable soft, flexible material, such as rubber, to prevent marring the finish of the automobile body or other sheet metal member against which it is applied.

Another object is to provide a tool of this character having a convex, substantially semi-spherical pressure head entirely covered with a soft resilient pad of rubber or the like.

A further object is to provide a pressure applying head of this character in which a peripheral flange or shoulder is formed at the inner side of the metal head and the peripheral portion of the rubber pad or cover is provided with an annular rib or channel adapted to fit over the same.

A still further object is to provide a pressure applying head of this character which may be in the form of a hollow metal casting having an internally screw threaded neck for detachable connection to a pressure applying strut, the head portion proper being convex and substantially semi-spherical and covered with a resilient pad of rubber or the like.

Another object is to provide a hollow, substantially semi-spherical rubber pad or cover for the pressure applying head having means thereon for detachably mounting it upon the metallic head.

A further object is to provide a simple, inexpensive, and durable pressure head of the character referred to, which is efficient in use and which will not mar or scratch surfaces against which it is applied.

The above objects together with others which will be apparent from the drawing and following

2

description, or which may be later referred to, may be constructed in the manner hereinafter described in detail and illustrated in the accompanying drawings in which;

5 Figure 1 is a perspective view of a hydraulic jack showing oppositely disposed tubular pressure applying struts connected to the base and the ram thereof and having a pressure applying head embodying the invention detachably connected to the outer end of each strut;

Fig. 2 a longitudinal, sectional view through a pressure applying head embodying the invention;

Fig. 3 a bottom plan view of the head shown in Fig. 2;

15 Fig. 4 a longitudinal sectional view through a modified form of the pressure applying head; and

Fig. 5 a bottom plan view of the head shown in Fig. 4.

Referring first to Figure 1 of the drawing, two 20 of the improved pressure applying heads to which the invention pertains are indicated at 10 and 11, detachably connected to opposite ends of the tubular pressure applying struts 12 and 13 respectively, which are shown detachably connected

25 to the base 14 and ram 15 of a hydraulic jack respectively, the cylinder of the jack being indicated at 16 and is arranged to be operated as by the pump 17 manually operated by the hand lever 18.

30 In the operation of this assembly the pressure applying heads 10 and 11 are placed against opposed portions of the automobile body, or other structure, to be straightened and by manual operation of the pump 17 by the handle 18 thereof,

35 the hydraulic jack is operated to move the ram 15 thereof outwardly forcing the pressure applying struts 12 and 13 in opposite directions and applying pressure against the objective portions of the automobile body through the pressure applying heads 10 and 11.

Referring next to the pressure applying head shown in Figs. 2 and 3, the head may be in the form of a hollow casting 19, of steel or other suitable material of sufficient strength. The head

45 comprises the convex, substantially semi-circular pressure applying head portion 20 having the annular rim shoulder or bead 21 around its periphery and terminating in the reduced, inwardly disposed tubular neck 22, internally threaded as at 23 for detachable connection to the threaded outer ends 24 of either of the tubular pressure applying struts 12 or 13.

50 For the purpose of protecting a painted or finished surface of automobile bodies, fenders or the like, against which the pressure applying head

may be applied, a soft resilient pad 25 of rubber or the like, entirely covers the convex surface 26 of the head, being preferably thicker at its central portion, as indicated at 27 and terminating in the inturned annular channel or rib 28 adapted to be hooked over the rim shoulder or bead 21 of the metal head so as to snugly hold the rubber pad upon the metal head.

In Figs. 4 and 5 is shown a slightly modified form of pressure applying head, this form being especially applicable to heads of smaller diameters. In this case the head 19a is also in the form of a hollow metal casting having the substantially semi-spherical head portion proper 20a with convex surface 26a terminating in the annular shoulder 21a, and provided with the inwardly disposed tubular neck 22a provided with the internal screw threads 23a.

The rubber pad 25a is of hollow, substantially semi-spherical form, so as to fit snugly upon the convex surface 26a of the metal head, and is preferably thicker at its central portion, as indicated at 27a, and terminates in the annular inturned member 28a for engagement over the annular shoulder 21a of the metal head.

From the above it will be obvious that a simple and efficient pressure applying head is provided, having a substantially semi-spherical surface for contact with an automobile body or other sheet metal part to be straightened or bent so as not to form any sharp ridge or cut therein and provided with a removable pad of rubber, or other suitable soft resilient material, for applying pressure against painted or finished surfaces so as not to scratch or mar the same.

I claim:

1. Apparatus for bending and straightening sheet metal members, comprising a pressure applying strut, a pressure applying head connected to the outer end of the strut, said head having a convex forward outer surface and an annular rearwardly disposed shoulder and a forwardly disposed annular channel at the inner side thereof, and a substantially semi-spherical hollow rubber covering fitting entirely over the convex outer surface of the head and having an inturned annular channel at its inner side fitting snugly over the annular shoulder on the head and terminating in a forwardly disposed bead extending into the forwardly disposed annular channel in the head.

2. Apparatus for bending and straightening sheet metal members, comprising a pressure applying strut having screw threads at its outer end, a pressure applying head having a threaded neck

detachably connected to said screw threads on the strut and having a convex forward outer surface and an annular rearwardly disposed shoulder and a forwardly disposed annular channel at the inner side thereof, and a substantially semi-spherical, hollow rubber covering fitting entirely over the convex outer surface of the head and having an inturned annular channel at its inner side fitting snugly over the annular shoulder on the head and terminating in a forwardly disposed bead extending into the forwardly disposed annular channel in the head.

3. Apparatus for bending and straightening sheet metal members, comprising a pressure applying strut, a pressure applying head connected to the outer end of the strut, said head having a convex forward outer surface and an annular rearwardly disposed rib and a forwardly disposed annular channel at the inner side thereof, and a substantially semi-spherical, hollow rubber covering fitting entirely over the convex outer surface of the head and having an inturned annular channel at its inner side fitting snugly over the annular rib on the head and terminating in a forwardly disposed bead extending into the forwardly disposed annular channel in the head.

4. Apparatus for bending and straightening sheet metal members, comprising a pressure applying strut having screw threads at its outer end, a pressure applying head having a threaded neck detachably connected to said screw threads on the strut and having a convex forward outer surface and an annular rearwardly disposed rib and a forwardly disposed annular channel at the inner side thereof, and a substantially semi-spherical, hollow rubber covering fitting entirely over the convex outer surface of the head and having an inturned annular channel at its inner side fitting snugly over the annular rib on the head and terminating in a forwardly disposed bead extending into the forwardly disposed annular channel in the head.
